UNITED STATES PATENT OFFICE

157,372

TOY ELEPHANT

Elisabeth Anne Philbrick Hall, Westwood, Mass.,
assignor to The National Pairpoint Company,
New Bedford, Mass., a corporation of Massachusetts

Application December 23, 1948, Serial No. 150,327

Term of patent 3½ years

(Cl. D34—2)

To all whom it may concern:

Be it known that I, Elisabeth Anne Philbrick Hall, a citizen of the United States, residing at Westwood, in the county of Norfolk and Commonwealth of Massachusetts, have invented a new, original, and ornamental Design for a Toy Elephant, of which the following is a specification, reference being had to the accompanying drawings, forming a part thereof.

In the drawings,

Fig. 1 is a perspective view of the front and left side of a toy elephant, showing my new design;

Fig. 2 is a perspective view of the front and right side of the toy elephant;

Fig. 3 is a side view, and

Fig. 4 is a rear view, of the toy elephant.

I claim:

The ornamental design for a toy elephant, as shown.

ELISABETH ANNE PHILBRICK HALL.
